UNITED STATES PATENT OFFICE.

JAMES O. BROWN, OF BOSTON, MASSACHUSETTS, ASSIGNOR OF ONE-HALF
TO JAMES S. NEWELL, OF SAME PLACE.

TREE-PROTECTOR.

SPECIFICATION forming part of Letters Patent No. 375,693, dated December 27, 1887.

Application filed May 12, 1887. Serial No. 237,993. (No model.)

To all whom it may concern:

Be it known that I, JAMES O. BROWN, of Boston, in the county of Suffolk and State of Massachusetts, have invented certain new and useful Improvements in Tree-Protectors, of which the following is a specification.

This invention relates to tree-protectors composed of metal hoops or bands which encircle the tree, and metal slats secured to said hoops, the hoops being constructed to expand, and thus increase in diameter with the growth of the tree. Heretofore the hoops have been constructed so that the ends of the metal strips of which they are made overlap and are secured by frictional clasps, which, while retaining said strips in hoop form, permit their ends to slip on each other, and thus expand with the growth of the tree, as shown in my application for Letters Patent of the United States filed December 13, 1886, Serial No. 221,443.

My present invention has for its object to improve the construction of the hoops with reference to their expansibility; and to this end it consists in a hoop having at one end a rotary bolt or rod adapted to rotate in a yoke or holder attached to the hoop, the opposite end of the hoop being engaged with and coiled upon said bolt, so that the hoop can expand 30 by the uncoiling of said coiled portion.

The invention also consists in certain details, all of which I will now proceed to describe and claim.

Of the accompanying drawings, forming a part of this specification, Figure 1 is a side elevation of a portion of a tree-protector provided with my improvement; Fig. 2, a section on line *x* *x*, Fig. 1; and Fig. 3 a side view of the yoke or holder and bolt.

40 The same letters of reference indicate the same parts in all the figures.

In the drawings, *a a* represent the hoops, and *b b* the slats composing the tree-protector, all being preferably made of strips of galvanized sheet-iron, the slats being slotted to receive the hoops, as shown in my above-named prior application. To one end of each hoop I attach a yoke, preferably by bending the hoop back over the cross-bar 2 of the yoke

and carrying the bent portion back through 50 the adjacent slat, *b*, and bending it again over one edge of said slat, as shown at 4, Fig. 2.

In the arms 33 of the yoke are formed orifices, which receive a bolt or rod, 5. Said rod is provided between said arms with a longitudinal slot, 7, adapted to receive the opposite end of the hoop-strip *a*. The rod also has a polygonal head, 6, adapted to be grasped by a wrench.

In applying the protector to a tree the slats 60 are placed upon the hoop strips, and the latter are then bent around the tree and one end of each hoop-strip is inserted in the slot of the rod 5 in the yoke on the other end of the same hoop-strip. The rod 5 is then rotated by a 65 wrench applied to its head 6 until a sufficient portion of the hoop-strip is coiled upon the rod to bring the hoop closely around the tree. It will be seen that the hoops thus formed will expand with the growth of the tree by the 70 uncoiling of the portions wound, as above described, upon the rods 5.

I prefer to enlarge the rods between the arms 33 of the yoke, so as to prevent the accidental removal of the rods from said arms. 75 This may be effected by inserting a suitable tool in the slots 7 and widening said slots, thus swelling the rods, as shown.

It will be seen that by this improvement I am enabled to entirely dispense with screw- 80 threads and clamping devices and make the construction of the hoops cheaper and more durable than heretofore.

It will be seen that the headed rotary bolts, adapted to be turned by a wrench, enable the 85 hoops to be tightened to any desired extent, so that the slats may be caused to bear closely against the tree and will not move laterally when the hoops expand. The slats will therefore remain evenly spaced, the spaces between 90 them increasing as the tree expands.

I claim--

1. A tree-protector hoop composed of a sheet-metal strip having at one end a yoke or holder and a slotted rod adapted to rotate 95 therein and to coil the other end of said strip, as set forth.

2. A tree-protector composed of hoop strips

each having at one end a yoke and rotary rod, on which the other end is coiled, and a series of slats supported by said hoops, as set forth.

3. The combination, in a tree-protector, of 5 a yoke, a hoop-strip bent at one end around the cross-bar of said yoke and partly around a strip on said hoop, and a rotatable rod in said yoke, on which the other end of the strip is coiled, as set forth.

In testimony whereof I have signed my name to this specification, in the presence of two subscribing witnesses, this 26th day of April, 1887.

JAMES O. BROWN.
